MANUFACTURING COMPANY, OF DUNEDIN, FLORIDA.

STRAP AND LINE REEL.

1,164,417.

Specification of Letters Patent. Patented Dec. 14, 1915.

Application filed November 14, 1914. Serial No. 872,134.

To all whom it may concern:

Be it known that I, BRONSON C. SKINNER, a citizen of the United States, and a resident of Dunedin, in the county of Pinellas and State of Florida, have invented a new and Improved Strap and Line Reel, of which the following is a full, clear, and exact description.

This invention relates to reels for holding box strapping, wire, rope and other stock, and has to deal more particularly with a brake or stop for abruptly stopping the rotation of the reel when the desired amount of stock is drawn off, so as to prevent the stock from unwinding and becoming tangled.

The invention has for its general objects to provide a comparatively simple, inexpensive and reliable stop mechanism for reels of the character referred to, the stop mechanism including a weighted lever or braking element which normally engages the reel frame to prevent rotation thereof in a direction to unwind the material from the reel, and which is automatically disengaged from the reel when a pull is exerted on the free end of the material, whereby the weight of the lever is overcome and the reel caused to rotate for permitting the unwinding of the material therefrom, and when the desired amount of material has been drawn off the pull on the brake lever is removed so that the latter will automatically engage the reel and abruptly stop the same and prevent its momentum from unnecessarily unwinding material from the reel.

With such objects in view, and others which will appear as the description proceeds, the invention comprises various novel features of construction and arrangement of parts which will be set forth with particularity in the following description and claims appended hereto.

In the accompanying drawings, which illustrate one embodiment of the invention, and wherein similar characters of reference indicate corresponding parts in both the views, Figure 1 is a side view of a reel for box strapping, showing the brake or stop lever in locking and unlocking position by full and dotted lines, respectively; and Fig. 2 is a plan view of the reel.

Referring to the drawing, A designates the stand, B the rotating reel and C the brake device for the latter. The stand A is

of any desired construction and embodies two triangular frames 1 rigidly connected together, and on the top of each frame is a bearing 2 for receiving the axle 3 of the reel B. This reel B comprises two sets of crossed arms 4 through which the shaft 3 extends, and the arms are provided with a series of openings 5 arranged successively at different radial distances from the axle, and bolts 6 pass through the openings to form supports for the coil D of box strapping. The bolts 6 can be placed in appropriate openings 5 according to the inner diameter of the coil of stock which the reel is to carry.

The stop device C comprises a lever formed of two bars 7 through which passes a bolt 8 that forms the fulcrum of the lever, and on the inner end of the lever is mounted a roller 9 which is adapted to engage the outer ends of any pair of arms 4 of the reel, as shown by full lines in Fig. 1. This engagement is effected by the outer part of the lever carrying a weight 10 slideable on one of the bars 7, whereby the weight tends to raise the inner end of the lever from the dotted to the full-line position. The stop lever C is intended to be automatically released from the reel by the act of pulling off material from the latter, and therefore the outer end of the lever C carries a pulley 10 mounted between and carried by posts 11 on the bars 7, and around this pulley the free end d of the box strapping passes. Thus, when the box strapping is pulled in a direction indicated by the arrow, Fig. 1, the outer end of the lever C is raised and the inner end lowered, so that the roller 9 will lie outside the path traversed by the outer extremities 4 of the reel, and consequently any amount of material can be unreeled. When, however, the unwinding pull is removed, the lever C automatically returns from the dotted to the full-line position, and thereby the roller 9 will lie in the path of the next arm 4 of the reel, and by engagement therewith stop the reel from rotation under its inertia. It will thus be seen that no more material will unwind from the reel than is desired, since the stopping of the pull will be accompanied by an immediate stopping of the rotation of the reel.

The frame of the machine is adapted to rest on the floor, ground or other horizontal surface, and the lever C projects out of the

frame A beyond the base thereof. Consequently when the reel is removed from the frame the weighted end of the lever will drop into contact with the horizontal surface on which the device is placed, thereby preventing the inner or reel-engaging end of the lever from ascending too high, so that when the reel is replaced it will engage the inner end of the lever and restore the same to normal or operative position. Thus no attention is required to be given to the lever, both in taking off or applying the reel.

From the foregoing description taken in connection with the accompanying drawings, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. A portable stand and reel device consisting of a stand comprising a base adapted to rest on the floor or ground, and a pair of upwardly extending frames rising from the base, a reel mounted on the upper portions of the frames and disposed between the latter and formed with arms, said reel being placed in the frame by a downward movement and removed therefrom by an upward movement, a brake lever pivoted on the stand at a point to one side of and be-

low the axis of the reel, and having one extremity extending under the reel to normally engage with the arms thereof and the other extremity extending out of the frame, said latter extremity being heavier than the first-mentioned extremity and so located as to gravitate to and strike the surface on which the stand rests when the reel is removed from the stand, and means on the lever for guiding the material as it is drawn off the reel, whereby a pull on the said unreeling material moves the brake lever out of engagement with the reel.

2. A portable stand and reel device consisting of a stand comprising a base adapted to rest on the floor or ground, and a pair of upright frames having bearings at their upper portions, a reel disposed between the frames and formed with arms, a horizontal axle disposed in the bearings and on which the reel is mounted, a horizontal lever having one arm disposed between the frames and under the reel to engage the arms thereof and the other arm extending out of the frame, a horizontal fulcrum on which the lever is mounted, a weight on the outer arm of the lever, whereby the inner arm is urged upwardly to engage the reel, and means on the outer end of the lever for guiding material unwound from the reel, whereby the pull on the unreeling material throws the lever out of engagement with the reel.

In testimony whereof I have signed my name to this specification in the presence of two subscribing witnesses.

BRONSON CUSHING SKINNER.
